UNITED STATES PATENT OFFICE.

JULIUS M. COLLINS, OF BROOKLYN, NEW YORK.

ASH-SIFTER.

1,229,033.

Specification of Letters Patent. Patented June 5, 1917.

Application filed May 23, 1916. Serial No. 99,342.

To all whom it may concern:

Be it known that I, JULIUS M. COLLINS, a citizen of the United States, residing at Brooklyn, in the county of Kings, State of New York, have invented certain new and useful Improvements in Ash-Sifters; and I do hereby declare the following to be a full, clear, and exact description of the invention, such as will enable others skilled in the art 10 to which it appertains to make and use the same.

This invention belongs to the class of ash sifters, and has particular reference to a gravity sifter.

15 The object of the invention, primarily, is to construct a sifter in which the presence of dust outside of the sifter is practically eliminated.

Those sifters which are known to me, even 20 those which confine the ashes within a sifting chamber permit more or less dust to escape at the inlet hopper for the ashes and at the exit spout for the cinders.

The present invention avoids the presence 25 of dust both at the inlet hopper and at the outlet spout for the cinders, a specially constructed cover for connecting the ash pail with the hopper being provided and also a special connection between the exit spout 30 and the pail for receiving the sifted material.

My invention further contemplates a particularly advantageous arrangement of gravity screens, which successively receive the 35 ashes and conduct the siftings to the outlet spouts, and permit the dust or fine material to drop into a dust receptacle.

With the above and other objects in view, which will hereinafter appear, my invention 40 will now be fully set forth and described, reference being had to the accompanying drawing.

In said drawing:—

Figure 1 is a front elevation of the sifter,

Fig. 2 is a side elevation thereof,

Fig. 3 is a section on line 3—3 of Fig. 1,

Fig. 4 is an enlarged detail view of the

hopper attachment for holding the ash pail,

Fig. 5 is a rear view of the part shown in

50 Fig. 4,

Fig. 6 is a detail view of the lower end of

the spout, looking from below, and

Fig. 7 is a detail perspective view of the

flexible hood used in connection with the invention.

55

Referring more particularly to said drawings, 1 represents a casing which is constructed of any suitable material, as metal or wood, and tapers laterally from its lower end to an outward intermediate point, and is then contracted so that its upper end narrows to a receiving opening 2. Within the casing 1 is mounted a plurality of sifting screens 3, 4 and 5. The screens 3 are mounted in angular relation in the upper portion of the casing 1, being carried upon the transverse rods 6 and 7. The rod 6 extends through the machine from front to back and supports the upper ends of the screens 3. From the rod 6, the screens incline in opposite directions to the rod 7 upon which the lower ends of the screens are supported. The screens 3 overlie a chute 8, said chute terminating at its lower end in a conduit 9 which slants toward the rear of the casing 1 and by means of the bend 10 which passes around the rear end of the screen 5. The screens 4 are secured at their upper ends upon the rods 11 which are carried in the front and rear walls of the casing 1 adjacent the sides 12 at the widest portion of the casing, and converge in a downward direction until their lower ends are carried by the bars or rods 13. Adjacent the lower ends of the screen 4, and located on an incline extending from the rear wall of the casing 1 to a lower point through the front wall, is the screen 5, which is supported upon the transverse bars 14 and 15. The screen 5 extends into an extension 16 formed on the front part of the casing 1 and forms the bottom of the spout 17, which projects forwardly and downwardly from the front of the casing 1.

105

An annulus cover 18 secured to the bottom of the casing and extension 16 provides a means for seating the sifting apparatus upon the top of a can, barrel or other receptacle. At the lower end of the spout 17 is provided a semi-circular cover and bracket 19, to whose forward straight side is hinged the cover section 20. The cover section 19 is downwardly flanged as at 21 and has the free edge of the flange 21 turned inwardly to provide the channel 22. Into said channel, the reinforced edge 23 of the bucket 24

is slid, and is therein held by closing the lid section 20 over the bucket, said lid section 20 is also flanged as at 25 to inclose the rim of the bucket. Hinged to the upper end or mouth 2 of the casing 1 is the device for attaching the pail containing the ashes to the casing 1. Said device consists of a chute portion 26, which is hinged to the rear edge of the opening or mouth 2 upon the hinges 27 the sides of the casing 1 overlapping the lower ends of the sides of the chute portion 26, to provide a dust-proof connection. The side walls of the chute portion 26 are connected by a transversely vertical wall 28, which is surmounted by an annulus 29. The annulus 29 provides a flange support for the rim of a pail 30, the annulus 29 standing in a vertical position, and being adapted to swing slightly beyond its vertical position 20 with the chute 26 so as to empty the pail of its contents, the cover provided by the annulus having an opening therethrough which corresponds to the section subtended by the rear vertical portion of the chute 26. 25 Below the annulus 29, the wall 28 is provided with a pair of hooks 31 which are, in effect, sheet metal plates provided with flanges for attachment to the wall 28, and having the upturned fingers 32 upon which the handle 33 of the pail 30 is adapted to be hooked, in order to lock the pail in position within the annulus 29. Covering the opening between the cover or annulus 29 and the chute portion 26, is a door or plate 34 which is 30 hinged at its upper edge substantially in the apex of the chute portion 26 upon the rod 35, so that it can gravitally swing upon a chute with the motion of the chute portion 26 upon the hinges 27. The hinged brace rods 36 and 37 are connected respectively to the sides of the casing 1, at the upper forward corner, and to the lower forward corners of the sides of the chute 26, said rods 36 and 37 acting as stops to limit the rearward 35 swing of the chute 26. The rod 36 is longer than the rod 37 and has its projecting end overturned as at 38 so that it will strike against the rod 37 and act as a stop to prevent the rods from having their longitudinal axes brought into perfect alignment. 40

Surrounding the mouth 2 and the lower end of the chute 26, is a hood 39, which may be made of foldable metal sections, or may 45 be also constructed of cloth or other suitable flexible material. When formed of flexible material, the hood is constructed of the triangularly shaped side pieces 40 and an intermediate section 41, the apexes of the 50 triangular side sections 40 being provided with eyelets 42 which project over the ends of the rod 43 which forms the pintle of the hinges 27.

In the operation of my improved appa-

ratus, the pail containing ashes to be sifted 65 is mounted in the chute 26, the rim of the pail being projected into the flange 29, and the handle or bail 33 being engaged with the hooks 31. This engagement having been effected, the chute 26 is swung upwardly in a 70 vertical position so that its mouth extends in to the upper end or mouth 2 of the casing 1. When the chute 26 is swung beyond the vertical position, the door 34 automatically swings open and permits the ashes 75 to drop into the casing 1. The ashes drop upon the screens 3, upon which they are partly sifted, the dust dropping into the chute 8. The cinders and the unsifted material drops then by gravity to the screens 80 4, and from the screens 4, the cinders drop to the screen 5 and pass thence to the spout 17, the dust from the siftings of the screens 4 and 5 dropping into the bottom of the casing 1 and thence into the receptacle upon 85 which the apparatus is mounted.

From the spout 17, the ashes pass into a bucket which has been mounted upon the combination holder and cover 19, the flange of the bucket being passed into the slide-way 21 and being locked therein by the flange 25 of the cover portion, which is 90 swung downwardly to cover the pail. The hood 39 covers the joint between the chute 26 and the mouth 2, so that all danger of 95 dust escaping from the mouth 2 is prevented, so that it is obvious that, by means of my improved apparatus one is enabled to sift ashes without the usual attendant dust which escapes even from the best types of 100 rotary and other sifters which are at present upon the market.

What I claim as my invention is:

1. An ash sifter comprising in combination, a casing, a plurality of relatively inclined screens mounted in said casing, said casing having a hopper mouth and a delivery spout, a chute hinged to said hopper mouth to drop backwardly therefrom, and means for locking a pail to said chute to be 110 carried up therewith into operative position.

2. An ash sifter comprising in combination, a casing, a plurality of sifting elements within the casing, a chute hinged to said casing to drop backwardly therefrom, and 115 means for locking a pail to said chute to be carried into an emptying position when the chute is lifted.

3. An ash sifter, comprising in combination, a casing, sifting elements within said 120 casing, a chute hinged to said casing to be dropped backwardly therefrom, a flexible covering for the joint between said chute and said casing, and means for locking a pail to said chute when the latter is carried 125 into delivery position.

4. An ash sifter, comprising in combination, a sifter casing, a feed chute hinged to

said casing, and means for limiting the relative movement of said chute, means for covering the mouth of a pail and locking the latter into dust-proof connection with the chute, and a gravity cut-off device for preventing the return of dust out of the chute after the pail has been removed.

Copies of this patent may be obtained for five cents each, by addressing the "Commissioner of Patents, Washington, D. C."

In testimony whereof, I affix my signature, in the presence of two witnesses.

JULIUS M. COLLINS.
